(57) **CLAIM**

The ornamental design for the expeller ring for a pump, as shown and described herein.

DESCRIPTION

FIG. 1 is a perspective view of the expeller ring depicting an outer side;

FIG. 2 is an elevation view of the outer side of the expeller ring shown in FIG. 1;

FIG. 3 is an elevation view of the expeller ring shown in FIG. 2, rotated 180°, illustrating the inner side of the expeller ring; FIG. 4 is a side view of the expeller ring shown in FIG. 2, rotated 90° to the left;

FIG. 5 is a side view of the expeller ring shown in FIG. 4 rotated 180°;

FIG. 6 is a side view of the expeller ring shown in FIG. 2 rotated horizontally 90° (x-axis) and then vertically 90° (y-axis);

FIG. 7 is a side view of the expeller ring shown in FIG. 6 rotated vertically 180°; and,

FIG. 8 is a perspective view of the expeller ring depicting the inner side as shown in FIG. 3.
